INTERNAL COMBUSTION ENGINE

Samuel B. Gold and Bruce E. Gold, Independence,
Mo., assignors to Weber Engine Company,
Kansas City, Mo., a corporation of Iowa

Application November 4, 1936, Serial No. 109,116

3 Claims. (Cl. 123—59)

This invention relates to internal combustion engines and more particularly to those of the two-cycle type wherein the combustion supporting air or a combustible fuel mixture is initially compressed and utilized for scavenging the burnt gases of a previous power impulse. Engines of this character, now in common use, are of low volumetric efficiency for the reason that they operate with excessive clearance volumes in order to keep the compression pressure of the air or mixture at a minimum, otherwise considerable power is lost because of the internal work required in effecting higher scavenging pressures. Another disadvantage is that in engines using gas as a fuel it requires five to twenty piston displacements per cylinder before the governor is effective in regulating the air and gas ratio responsive to load variations on the engine, consequently the mixtures of gas and air in the power and compression chambers are never uniform with the engine load.

It is, therefore, the principal object of the present invention to provide a two-cycle engine wherein the air or mixture is handled to give high volumetric efficiency with low scavenging pressures and with minimum internal loss of power incidental to compression of the air or mixture admitted to the combustion chamber.

It is also an important object to eliminate the lag between changes in the fuel ratio responsive to variations in the engine loads.

Other important objects of the invention are to provide a simplified engine construction which permits of splash lubrication in the crank case; to provide efficient, economic means of lubricating moving parts of the engine; to provide mechanism for compression of the combustion supporting medium that will operate equally well in engines using gas or liquid fuels; to provide automatic pressure means for controlling flow of fuel to the engine; to provide for uniform admission of the combustion supporting medium or mixture to each of a number of cylinders; and to effect admission of the medium in a manner to thoroughly scavenge the cylinders of burnt gases without loss of medium through the exhaust ports.

In accomplishing these and other objects of the invention, as hereinafter described, we have provided improved details of structure, the preferred form of which is illustrated in the accompanying drawings, wherein:

Fig. 1 is a vertical section through a two cylinder, two-cycle internal combustion engine embodying the features of the present invention and

showing a piston in one of the cylinders at the end of its power stroke and the piston in the other cylinder at the beginning of its power stroke.

Fig. 2 is a cross-section through the engine on the line 2—2 of Fig. 4.

Fig. 3 is an end view of the engine, particularly illustrating the fuel supply mechanism, the governor controlling the amount of fuel supplied and the mechanism for supplying lubricant to the respective working parts of the engine.

Fig. 4 is a horizontal section through the engine on the line 4—4 of Fig. 2.

Fig. 5 is an enlarged detail section through the automatic shut-off valve for controlling flow of fuel medium to the engine.

Fig. 6 is a detail section through the air and fuel inlet to the engine.

Fig. 7 is a detail cross-section through the lower portion of the engine particularly illustrating the method of lubricating the main bearings.

Fig. 8 is a horizontal section extending through the intake and exhaust ports of one of the engine cylinders, and showing the directional flow of the fuel mixture or scavenging medium relatively to the flow of exhaust gases.

Fig. 9 is an enlarged perspective section through one of the cylinders to better illustrate flow of the fuel mixture or scavenging medium.

Fig. 10 is a view of an indicator card showing the pressures in the reservoir supplying the respective pistons.

Fig. 11 is a view of a similar card showing the pressures occurring in one of the charging cylinders.

Fig. 12 is a section through one of the intermediate inlet ports of a combustion chamber on the line 12—12 of Fig. 8.

Fig. 13 is a similar section through one of the outer inlet ports on the line 13—13 of Fig. 8.

Referring more in detail to the drawings:

1 designates a two-cycle internal combustion engine which is constructed in accordance with the present invention and includes a crank case 2 comprising a base portion 3 and an upper or cover portion 4. The base portion 3 is provided with transverse bearing supports 5, 6 and 7 to rotatably mount a crank-shaft 8. The crank-shaft 8 includes bearing portions 9, 10 and 11 rotatably mounted in bearings 12, 13 and 14 carried by the respective supports 5, 6 and 7, half of each bearing being formed in the respective supports and the other half in caps 15 that are secured to the supports by suitable stud bolts as in conventional practice. The crank-shaft has cranks 16 and 17 positioned between the spaced 55

bearings to connect piston rods 18 and 19 carrying pistons 20 and 21 that are connected therewith by the conventional wrist pins 22 and 23. The upper half 4 of the crank case is secured to the lower portion by stud bolts 24 that are extended through aligning lugs 25 and 26 formed on the respective portions as best shown in Fig. 2. The respective ends of the crank case are closed by end plates 27 and 28 that are provided with sealed openings 29 and 30 through which ends of the crank-shaft extend for respectively mounting a fly wheel 31 and a ratchet type starting crank 32 whereby the crank-shaft is rotated to initially start operation of the engine or position the pistons for operation of an air starter where used. Supported by the upper half of the crank case are parallel side walls 33 and 34 and end walls 35 and 36 connected by horizontally spaced partitions 37 and 38 to support charging cylinders 39 and 40 above each of the cranks 16 and 17.

The charging chambers include cylindrical walls 41 cooperating with the end walls 35-36, the side wall 33, a wall 42 inset from the other side wall 34, and webs 43 and 44 to form a closed transfer reservoir 45 having connection with the respective charging chambers through ports 46 that are formed in the side walls of the cylinders and which are normally closed by valve plates 47 attached to a seating flange 48 circumscribing the boundary of the respective ports.

The valve plate 47 includes a frame having a plurality of outlet openings 49 that are normally closed by leaf springs 50 each having one of their ends attached to the frame of the valve plate 35 and their opposite ends free to move to and from valving relation with their respective openings, the springs being mounted on the outlet side of the openings to seat thereagainst when pressure in the transfer reservoir exceeds the pressure within the charging chambers.

Formed in the opposite side of the chambers are inlet ports 51 circumscribed by flanges 52 connecting the walls of the charging cylinders with the inset partition 42. Formed in the partition in alignment with the inlet ports are openings 53 and 54 that are covered by valve plates 55 having slotted openings 56 therein that are normally closed by leaf springs 57 having their intermediate portions 58 fixed to transverse bars 59 of the valve plates so that the ends thereof are free to move to and from covering relation with the slotted openings, and which are adapted to automatically open responsive to suction pressures within the charging chambers to permit flow of charging fluid therethrough from a manifold space 60 having an inlet port 61 that is formed in the side wall 34 at a point substantially midway of the length of the crank case.

Fixed to the side wall and extending over the inlet opening 61 is an air and fuel mixing device 62 having a flat plate portion 63 that is seated against the side wall and has a peripheral flange 64 extending laterally therefrom to form an annular seat for a filtering diaphragm 65 that is clampingly supported thereagainst by a covering cap 66. The cover cap 66 is spaced from the filtering diaphragm to form an air passage 67 into which atmospheric air is drawn through lateral ports 68 formed at the side edges of the cap.

Extending inwardly from the plate portion, in encircling relation with the opening 61, is a circular flange 69 that cooperates with an inwardly extending flange 70 of a ring 71 to provide an annular fuel distributing chamber 72 that communicates with the opening 61 through an annular slot 73. Fuel is admitted to the annular chamber through a tangential inlet port 74 that is connected by a pipe 75 with an automatically operated valve 76 which controls admission of fuel to the respective charging chambers responsive to suction pressures that are created therein.

The valve 76 includes upper and lower diaphragm supporting sections 77 and 78 that are secured together to form pressure chambers 79 and 80 on the respective sides of the diaphragm. Formed as a part of the lower section 78 is a valve housing 81 having inlet and outlet ports 82 and 83 respectively connected between sections of the supply line 75.

The inlet port 82 communicates with the pressure chamber 80 through a passage 84 and the outlet port 83 communicates with the chamber 80 through a port having a valve seat 85 that is adapted to be closed by a valve 86. The valve 86 may be of any approved construction and is operated by the diaphragm responsive to differential pressures on the respective sides thereof. The pressure chamber 79 is open to atmosphere and contains a coil spring 87 that seats against the diaphragm and against a spring seat 88 that is supported by an adjusting screw 89. It is thus apparent that when the pressure in the passage 84 is greater than the pressure acting on the opposite side of the diaphragm the valve is closed against action of the spring 87. However, when the engine is in operation and fuel is being drawn through the pipe 75, the pressure in the valve chamber 80 drops sufficiently to allow the spring 87 to move the valve to open position.

The inlet end of the pipe 75, or that section connected with the port 82, is attached to a throttle valve 91 that is operated by a governor 92 in conformance with the load requirements of the engine, as in conventional practice, so that the fuel is admitted in proportion to the load demand acting on the engine, the governor being actuated by a suitable connection with the crank-shaft.

Carried by the crank case, in concentric alignment with each of the charging cylinders, are power cylinders 93 and 94 having combustion chambers 95 and 96 in which the pistons 20 and 21 are respectively mounted. The diameters of the combustion chambers are smaller than the diameters of the charging chambers so that skirt portions 97 and 98 on the respective pistons cooperate with the charging cylinders to form annular charging chambers 99 and 100.

Formed as a part of each piston, and on the lower end of the respective skirts, are charging pistons 101 and 102 having sliding contact with the walls of the charging chambers so that when the pistons are reciprocated the charging pistons act to draw in an air and gas mixture and to compress the mixture for discharge into the transfer reservoir, as later described.

The cylinders 93 and 94 are preferably water-jacketed, as indicated at 103, and have their lower ends inset into the upper ends of the charging cylinders so that there is only slight clearance between the charging pistons and the lower end of the cylinders when the pistons are on their respective top dead center positions. The cylinders are preferably mounted on the plate portion 37 of the crank case by means of laterally extending flanges 104 through which bolts 105 are projected, as best shown in Fig. 1. The upper ends of the cylinders are closed by cylinder heads 106 having ignition chambers 107 communicating directly with the combustion chambers. The cylinder 75

heads carry suitable ignition devices, such as spark-plugs 108, to ignite the fuel charges when they are drawn into the combustion chambers. Formed in the lower end of each cylinder are 5 passageways 109 having inlets 110 communicating with the transfer reservoir and having connection with the combustion chambers through inner and outer pairs of intake ports 111-112 and 113-114 respectively.

0 The inner ports 111-112 are of greater height than the outer ports and are arranged, as shown in Figs. 8, 9 and 12, to inject the admitted fuel in upwardly directed streams converging at a point offset from the axis of the cylinder midway between the respective ports. The streams of charging medium admitted through the outer ports 113-114 are directed more horizontally and under the impinging streams admitted through the central ports so that they act in moving the 10 impinging streams upwardly in parallel relation and moving contact with one side of the cylinder toward the combustion chamber and across the top of the combustion chamber to the opposite side wall of the cylinder and then downwardly 15 toward exhaust ports 115 that are formed in the opposite side walls of the respective cylinders to push the exhaust gases therethrough. The mixture drawn in thus scavenges the cylinders of burnt gases and fills them with a combustible 20 mixture that is compressed for ignition upon the upstrokes of the respective pistons. The exhaust ports communicate with manifold chambers 116 having outlets 117 to a common exhaust manifold 118 that is secured to the sides of the respective 25 cylinders as shown in Fig. 2.

In order to lubricate the cylinders, the end of the crank case supporting the governor and throttle mechanisms mounts a lubricator 119 having lines 120 leading to oil ports 121 formed in the 0 walls of the cylinders as best shown in Fig. 1. One of the lead lines of the lubricator extends to the governor to lubricate the governor mechanism.

The crank shaft and connecting rod bearings, as well as the walls of the charging cylinders, are lubricated by combination splash and direct feed of lubricating oil from a power driven pump 122 that is actuated from the crank-shaft and which pumps oil from the bottom of the crank case through a screen 123 and delivers it to an oil 40 reservoir 124 that is formed in the bearing support 7.

Extending from the reservoir 124 are oil lines 125 leading to splash pans 126 that are supported below each of the connecting rods, the oil being supplied therethrough in ample amounts to maintain the pans in full condition so that there is an adequate supply of oil to be splashed by means of dippers 127 carried on the respective connecting rods and adapted to dip into the pans upon each 45 revolution of the cranks. Other lines 128 extend to sumps formed in the caps of the respective bearing supports for flow to the bearing portions of the crank-shafts through ports 129. Excess oil in the bearings flows through ports 130 to sumps 131 carried by the bearing supports 5, 6 and 7. The oil level in the sumps is above the bottom of the crank-shaft bearing so that there is a bath of oil in the bearing at all times, regardless of the variation in the amount supplied by the pump. From 50 the bearings the oil returns to the bottom of the crank case where it is again drawn through the filter and recirculated by the pump.

The operation of an engine constructed and assembled as described is as follows:

5 A gaseous fuel is delivered to the engine through

the throttle valve 91 under control of the governor 92. Upon cranking the engine suction created within the effective charging chambers, that is the one in which the charging piston is moving downwardly, effects opening of the diaphragm valve 86 5 to allow admission of the fuel into the circumferential space 72 from where it is drawn through the annular slot 73 under the inducing action of air drawn through the air filter 65. Upon entering the valve chamber the air and gas are mixed 10 incidental to the circumferential movement of the fuel. During the downstroke of the charging piston, the fuel mixture is drawn through the openings in the valve plate 55 for that cylinder unseating the spring leaf valves for flow into the 15 charging chamber for the entire stroke of the piston. On the upstroke the spring leaves of the inlet valve seat while the spring leaves on the discharge valve for that cylinder unseat to allow flow of the fuel mixture into the transfer reservoir. 20 Attention is here directed to the fact that since the valves automatically open by reason of pressure differentials on the respective sides thereof the charge drawn into the charging chamber is expelled during the entire upstroke of the piston, 25 thereby eliminating any back pressure other than that caused by the pressure contained in the transfer reservoir prior to uncovering of the intake ports of the combustion chamber of the other cylinder. 30

When the charging piston has substantially reached the upper limit of its travel the power piston for the other cylinder has uncovered the intake ports so that the fuel mixture passes from the transfer reservoir into the combustion chamber for that cylinder. The relative capacities of the respective charging chambers and transfer reservoir are such that the pressures in the transfer reservoir seldom exceed three to five pound pressure and when the mixture has passed into the combustion chamber of the other cylinder, the pressure in the transfer reservoir drops to substantially atmospheric pressure. Therefore, a minimum of internal power is required in operating the charging pistons since the fuel mixture is 40 compressed only sufficiently to effect scavenging of the exhaust gases from a previous power cycle of the cylinder into which the fuel mixture is 45 delivered.

By observing Figs. 8 and 9, it will be noted that 50 the outer pair of intake ports 113 and 114 direct separate jets of the fuel mixture into impinging relation at a point substantially midway between the axis of the combustion chamber and the wall thereof. Simultaneously the inner pair of intake 55 ports 111 and 112 effect discharge of impinging jets at a point slightly above the impinging point of the jets admitted through the outer ports. This is accomplished by different angular relationship of the pairs of ports to the axis of the combustion 60 chamber and also by the different angular inclinations of the inner and outer ports, as clearly illustrated in Figs. 12 and 13.

The inner ports are slightly higher than the outer ports so that the jets of fuel begin to be 65 admitted therethrough slightly prior to opening of the outer ports, thereby assuring that the jets admitted through the one set of ports act in upwardly lifting relation with the jets admitted through the other set of ports to cause the fuel 70 mixture to move upwardly adjacent that side wall of the combustion chamber and across the ignition chamber 107 to sweep the burnt gases there-ahead and downwardly at the other side of the cylinder and through the exhaust ports, as clearly 75

shown by the arrows in Fig. 9. We are thereby enabled to provide thorough scavenging of the combustion chamber with the low pressures as above noted.

5 The admission of the respective jets of fuel mixture at different elevations also causes deflection of the indrawn mixture without the aid of deflector plates on the piston head as is usually the practice in this type of engine. When 10 the pistons move on their other cycle the charge is compressed and ignited by means of the spark-plug 108 as in conventional practice. During the power stroke another charge is being drawn into the charging chamber of that cylinder to be 15 discharged into the corresponding combustion chamber of the other cylinder for continuous operation of the engine. It is thus obvious that the fuel drawn into the charging chamber of one cylinder is utilized in the combustion chamber 20 of the other cylinder and vice versa, thereby eliminating the necessity of storage chambers and at the same time effecting high volumetric efficiency with low scavenging pressures.

What we claim and desire to secure by Letters 25 Patent is:

1. An internal combustion engine including combustion chambers having intake ports in the sides of the chambers and having exhaust ports at the opposite sides thereof, charging chambers 30 having intake and discharge ports, a transfer reservoir providing a common connection between the discharge ports of the charging chambers and all of the intake ports of the combustion chambers, pistons reciprocable in the combustion 35 chambers and movable over the intake and exhaust ports of said combustion chambers, valves in the discharge ports of the charging chambers automatically operable responsive to differential pressures in the transfer reservoir and charging chambers, means in the charging chambers for drawing a charging medium into said chambers through the intake ports thereof and discharging said medium through said pressure responsive valves for transfer to the combustion chambers when the pistons uncover the intake ports to effect scavenging of exhaust gases through the exhaust ports of said combustion chambers and effecting charging of the combustion chambers, and valves controlling the intake ports of the charging chambers, the intake ports of the combustion chambers being of different capacities and arranged so that certain of said intake ports of the combustion chambers are uncovered by the respective pistons in advance of opening of 55 the other intake ports whereby the portion of the charging medium admitted from the transfer reservoir through the first opened ports is caused to move upwardly along the sides of the combustion chambers and the portion of the charging 60 medium admitted from the transfer reservoir through the second opened ports is caused to flow under that admitted through the first opened ports to maintain movement of the medium to the upper end of the combustion chambers during the time said exhaust ports are opened by the pistons.

2. In an engine of the character described, a

combustion chamber having different sized intake ports in a side of the chamber and having an exhaust port at the opposite side, common transfer means connecting all of said intake ports, a piston operable in said chamber for admitting a charging medium from the transfer means through the intake ports and having an upwardly and inwardly directed deflecting portion movable across said intake ports, the larger of said intake ports being arranged to be uncovered by the piston in advance of the smaller port whereby the portion of the charging medium admitted through the larger port from the transfer means is caused to move upwardly along the side of the combustion chamber having the intake ports to expel products of combustion from a previous charge down the opposite side and through the exhaust port and the portion of the charging medium admitted through the smaller port is subsequently deflected and caused to flow under that admitted through the larger port.

3. In an internal combustion engine, a combustion chamber having a plurality of intake and exhaust ports arranged in arcuate series on the respective sides of the combustion chamber, a charging chamber located in axial alignment with said combustion chamber and having intake and discharge ports, transfer means connecting the discharge port of the charging chamber with all of the intake ports of the combustion chamber, a power piston reciprocable in the combustion chamber and movable over the intake and exhaust ports of said combustion chamber, valve means controlling the discharge port of the charging chamber automatically operable responsive to differential pressures in the transfer means and the charging chamber, a charging piston connected with the power piston and operable in the charging chamber to draw a charging medium into said chamber through the intake port and discharging said medium through said pressure responsive valve into the transfer means for transfer to the combustion chamber when the power piston uncovers the intake ports to effect scavenging of the exhaust gases through the exhaust ports of said combustion chamber and to effect charging of the combustion chamber, and valve means controlling the intake port of the charging chamber, one of said intake ports of the combustion chamber being arranged to be uncovered by the power piston in advance of another of said intake ports whereby the portion of the charging medium admitted from the transfer means through the first opened port is caused to move upwardly along the side of the combustion chamber and a portion of the charging medium admitted from the transfer means through the second opened port is caused to flow under that admitted through the first opened port to maintain movement of said medium to the upper end of the combustion chamber during the time said exhaust ports are opened by the piston.
